UNITED STATES PATENT OFFICE.

ALONZO B. ARNOLD, OF GLADBROOK, IOWA, ASSIGNOR OF TWO-THIRDS TO
DAVID H. GOTSHALL AND PAUL L. FEDDERTON, OF SAME PLACE.

NECK-YOKE COUPLING.

SPECIFICATION forming part of Letters Patent No. 340,972, dated May 4, 1886.

Application filed November 23, 1885. Serial No. 123,673. (No model.)

To all whom it may concern:

Be it known that I, ALONZO B. ARNOLD, a citizen of the United States of America, and a resident of Gladbrook, in the county of Tama 5 and State of Iowa, have invented an Improved Neck-Yoke Coupling, of which the following is a specification.

My object is to improve the appearance and durability of a metal coupling device, 10 adapted to connect a yoke with the pole of a vehicle without increasing its cost; and my invention consists in the construction and combination of a pole-tip having a bearing for a cross-bar, a cross-bar having journals on its 15 ends and rabbets in its edges, and elbow-shaped clips, as hereinafter set forth, pointed out in my claims, and illustrated in the accompanying drawings, in which—

Figure 1 is a front view of my complete device attached to a section of a yoke; Fig. 2, a 20 top view of the cross-bar having journals on its ends pivoted in the bearing on the pole-tip, and Fig. 3 a perspective view showing a neck-yoke and pole connected by means of my invention as required for practical use.

A is a malleable-iron pole-tip, of common form, that I provide with integral flanges b b, that extend toward each other and over a flat surface on the top and center of the tip, to produce a bearing within which to pivot and operate a cross-bar.

c is a straight metal bar, that has journals on its ends and rabbets in the top sides of its curved edges, that admit the flanges b, as clearly 35 shown in Fig. 2.

d is a rivet that extends through perforations in the pole-tip and bar, and forms a pivot upon which the bar c can turn in the bearing on the top side of the tip, as required, to allow 40 the neck-yoke f horizontal vibratory motion. The flanges b in the rabbets in the edges of the bar c aid in retaining the bar in its place and relieve the pivot from strain. When they become worn, or do not fit closely in the rabbets 45 in the edges of the bar, they can be readily bent downward when made of malleable iron and integral with the tip, as contemplated.

g g are elbow-shaped metal clips fitted to the

yoke f, and fastened thereto by means of wood-screws, as shown in Fig. 1. The parts that 50 project downward have perforations to admit the journals on the ends of the pivoted bar c, and to thereby suspend the bar and pole-tip jointly, as required, to allow the yoke to swing backward and forward relative to the pole h, 55 that is slipped into the pole-tip, as shown in Fig. 3.

A complete metal coupling device is thus produced by the combination of four metal 60 castings, that can be readily applied to connect a yoke and pole in such a manner that the yoke and pole will have free independent motions, as required, to prevent the chafing and striking of horses incident to the use of neck-yokes.

I am aware that a ring or pole-tip having a conical upward extension has been riveted to a cross-bar having journals on its ends, and the pole-tip and cross-bar thus combined then connected with a bar or yoke by means of eye-bolts; but the head of the rivet is subjected to bear all the vertical pressure of the pole and too much friction and wear, and soon becomes worn and unsafe, and I overcome such defect and relieve the pivot from vertical pressure 70 and strain and wear by means of the flanges formed integral with the pole-tip and the rabbets on the edges of the cross-bar pivoted to the pole-tip.

I claim as my invention—

1. In a neck-yoke coupling, the combination of a pole-tip having a flat surface and flanges b at the edges of the flat surface, and a bar, c, having rabbeted edges to extend under said flanges, substantially as and for the 85 purposes stated.

2. The improved neck-yoke and pole coupling composed of a pole-tip having a flat surface and flanges b, a bar, c, having journals on its ends and rabbets in its edges, and elbow-shaped clips g, substantially as shown and described.

ALONZO B. ARNOLD.
